UNITED STATES PATENT OFFICE.

ALBERT D. PALMER, OF PITTSBURGH, PENNSYLVANIA, ASSIGNOR TO JOHN GERNERT,
OF PITTSBURGH, PENNSYLVANIA.

ATTACHMENT FOR PIANOS OR THE LIKE.

1,007,232.

Specification of Letters Patent. Patented Oct. 31, 1911.

Original application filed May 14, 1909, Serial No. 495,914. Divided and this application filed January 16, 1911. Serial No. 602,989.

To all whom it may concern:

Be it known that I, ALBERT D. PALMER, residing at Pittsburgh, in the county of Allegheny and State of Pennsylvania, have 5 invented certain new and useful Improvements in Attachments for Pianos and the Like, of which the following is a specification.

This invention relates to an attachment 0 for pianos, piano players, organs and the like having pedals for controlling the volume of the tones played, and it generally has for its object to provide electromagnetically operated means controlled by the pedal of an 15 ordinary piano or other like instrument, for using a bass drum.

This application is drawn to cover matter 20 eliminated from my application filed May 14, 1909, Serial No. 495,914, on which Patent #956,502 was issued April 26, 1910.

It is the object of my invention to provide an attachment of the foregoing character that may be applied to any ordinary make 25 of piano, or other similar instrument, without out in any way damaging or requiring a rebuilding of the instrument.

In its more detail nature this invention also comprises those details of construction, combination and arrangement of parts, all 30 of which will be first described in detail, then be specifically pointed out in the appended claims, and illustrated in the accompanying drawings, in which:—

Figure 1 is a side elevation of a bass drum 35 and cymbal with my invention applied, the piano pedals being indicated. Fig. 2, is a detail view of a part of the invention.

Referring now to the accompanying drawings in which like letters and numerals of 40 reference indicate like parts in all of the figures, it will be observed that the bass drum 15 and cymbal 16 are actuated by a magnetically-actuated drum stick 17 that is pivoted at 18 to a bracket 19 that is secured 45 to the drum. The drum stick 17 has an extension 17^a that carries the armature 17^b to coöperate with the magnet 20. The magnet 20 is electrically connected to a battery 21 by a wire 21^a and is also electrically 50 connected to a rheostat 22 by a wire 22^a, the rheostat lever arm 22^b being connected by a wire 22^b with a contact 23^a that coöperates with a second contact 23^b to close the circuit from the battery 21 through the

magnet 20 and rheostat 22. The battery 21 55 is connected with contact 23^b by a wire 21^b. The contacts 23^a—23^b are brought into engagement with one another through the action of the center or "practice" pedal 23 of a piano, so that the operator upon depressing the pedal 23 will close the contacts 23^a—23^b respectively, and energize the magnet 20, which draws over the armature 17^b and causes the drum stick 17 with its hammer 17^x to strike the head of the drum, and 60 at the same time by adjusting the cymbal clapper 16^x the cymbal 16 may be struck. The taps may be imparted to the drum at will by merely depressing the pedal 23 but the force of the tap is regulated by adjusting 65 the rheostat.

It is, of course, obvious that slight changes in the details of construction and arrangement of parts may be made without departing from the spirit of the invention or the 75 scope of the appended claims.

What I claim is:

1. In combination with a pedal, a bass drum, a bracket secured thereto, a drum stick pivoted to said bracket and having an 80 armature, an electromagnet supported by said bracket to operate said armature and drum stick, an electric circuit including said magnet, a pair of contacts in said circuit to be moved by said pedal to close the circuit, and a source of energy for energizing 85 said circuit.

2. In combination with a pedal, a bass drum, a bracket secured thereto, a drum stick pivoted to said bracket and having an 90 armature, an electromagnet supported by said bracket to operate said armature and drum stick, an electric circuit including said magnet, a pair of contacts in said circuit to be moved by said pedal to close the circuit, 95 a source of energy for energizing said circuit, and a rheostat in said circuit to vary the force of action of said magnet.

3. In combination with a pedal, a bass drum, a bracket secured thereto, a drum 100 stick pivoted to said bracket and having an armature, an electromagnet supported by said bracket to operate said armature and drum stick, an electric circuit including said magnet, a pair of contacts in said circuit to 105 be moved by said pedal to close the circuit, a source of energy for energizing said circuit, and a rheostat in said circuit to vary the

force of action of said magnet, a cymbal carried by said drum, and a cymbal clapper on said drum stick for engaging said cymbal.

4. In combination with a pedal, a bass drum, a bracket secured thereto, a drum stick pivoted to said bracket and having an armature, an electromagnet supported by said bracket to operate said armature and drum stick, an electric circuit including said 10 magnet, a pair of contacts in said circuit to

be moved by said pedal to close the circuit, and a source of energy for energizing said circuit, a cymbal carried by said drum, and a cymbal clapper on said drum stick for engaging said cymbal.

ALBERT D. PALMER.
